United States Patent Office.

DAVID M. SWAIN, OF LA CROSSE, WISCONSIN.

Letters Patent No. 67,608, dated August 6, 1867.

IMPROVEMENT IN BOILER WATER-GAUGES.

The Schedule referred to in these Letters Patent and making part of the same.

TO ALL WHOM IT MAY CONCERN:

Be it known that I, DAVID M. SWAIN, of La Crosse, in the county of La Crosse, and State of Wisconsin, have invented a new and useful Improvement in Water-Gauges; and I do hereby declare and make known that the following is a full, clear, and exact description of the same, reference being had to the accompanying drawings, and the letters and figures marked thereon, which form part of this specification.

My invention consists in a novel arrangement of mechanical devices whereby the engineer or others can readily ascertain the height to which the water rises in the boiler by inspecting a dial-face, or by the sound of a whistle when the water is down as low as is compatible with safety, so that water may be seasonably introduced into the boiler, thereby preventing explosions.

To enable those skilled in the art to understand how to construct and use my invention, I will proceed to describe the same with particularity, reference being made to the aforesaid drawings, in which—

Figure 1 represents a front elevation of my invention.

Figure 2, a side elevation of the same, and

Figure 3 a rear view, the plate K being removed.

Similar letters of reference in the several figures denote the same parts of my invention.

The gauge-face or dial is arranged upon the boiler, the tube E passing through the boiler-plate into the boiler. A represents a hollow water-tight metallic globe, which rests upon the surface of the water, and has attached thereto an arm, B, which screws into a bar, C, which is suspended in the support D by means of the pivots α upon said bar and the set-screw c . If preferred the arm B and bar C may be of a single piece. By suspending or pivoting the arm B C upon the prolonged points α , there is much less liability of the parts becoming fixed from incrustation or deposit upon the joint than when suspended in the usual manner, and the ordinary guides for the end of the bar C are also dispensed with. To the rear end of C is connected a rod, F, which passes loosely up through the tube E into a chamber, J, which is rendered steam-tight in any suitable manner, where the upper end of said rod is attached to an arm, G, projecting a suitable length, as shown, from a shaft, b, which passes through to the front, as shown, where there is attached a toothed segment, d. The pointer is attached to a separate shaft, upon which is attached a pinion, e, which gears into the said toothed segment upon the shaft b, as seen in fig. 1. S represents a coil spring, which is attached to the shaft upon which the pointer B is arranged in such a manner as to hold the teeth of the pinion firmly against the teeth of the segment, so that all lost motion is avoided, and the movement of the pointer insured at the slightest variation in the position of the float. Upon the shaft b is fixed an arm, H, which, as the float sinks, is brought in contact with a shoulder, I, which opens the port in the whistle, when the steam from the chamber J enters and sounds the whistle.

Having described the construction and operation of my invention, I will now specify what I claim and desire to secure by Letters Patent:

I claim the float A and its arm, the supports D, rod F, arm G, shaft b, segment d, pinion e, pointer P, spring S, arm H, and shoulder I, arranged and operating substantially in the manner and for the purposes specified.

DAVID M. SWAIN.
